MEASURING DISPENSING APPARATUS FOR FLUIDS

Filed March 18, 1931

UNITED STATES PATENT OFFICE

JESSE CONRAD SMITH, OF NEW YORK, N. Y., ASSIGNOR TO INTERNATIONAL PRODUCTS CORPORATION, OF NEW YORK, N. Y., A CORPORATION OF NEW YORK

MEASURING-DISPENSING APPARATUS FOR FLUIDS

Application filed March 18, 1931. Serial No. 533,400.

The object of the present invention is to provide a compact, inexpensive and efficient dispensing device particularly adapted for dispensing bouillon and like liquids from an inverted original jar. That is to say, the container for the bouillon may be used as the supply holder for the dispensing apparatus.

The particular object of the invention is to enable leakproof connection of the container to the apparatus while the container is in normally upright position.

A further object of the invention is to maintain the leakproof arrangement of the elements without the use of washers or other soft members between the moving parts.

Other objects will hereinafter appear.

The invention will be described with reference to the accompanying drawing in which

Fig. 1 is a view in elevation showing an embodiment of the invention.

Fig. 2 is a sectional plan view on the line 2—2, Fig. 1.

Fig. 3 is an enlarged vertical section on the line 3—3, Fig. 2.

Fig. 4 is a fragmentary vertical section on the line 4—4, Fig. 2.

Fig. 5 is an enlarged detailed vertical section through the jar-holding plate showing its outlet closed by the closure plate of the dispensing cup and the latter in position for discharge.

Referring to the drawing, it will be seen that the device comprises a flat base member 1 to which are fastened the opposed metal standards 2, each formed at its upper end with the spaced supporting arms 2a. The standards may be riveted to the base member or formed integrally therewith. In the present embodiment, the standards are formed at their lower ends with flanges apertured to receive fastening screws 3 by means of which they are secured to the base member 1.

Removably mounted upon the standards 2 is a horizontal plate 4 which supports the dispensing mechanism and also the supply container for the material to be dispensed, as, for example, bouillon. To this end, holding

plate 4 is provided at opposite ends with legs 4a; each leg being formed with underlying vertical recesses so as to receive one of the arms 2a shown more particularly in Figs. 1 and 2. The plate 4 centrally thereof is provided with an upwardly extending annular flange 5 and the plate centrally of the flange is apertured as at 6 for the passage of material from the supply container.

Intermediate the aperture 6 and the inner wall of annular flange 5 means are provided for holding a closure member for the supply container. In the present embodiment, the horizontal wall of plate 4 at such point is provided with spaced threaded apertures 55 to receive screws 7 which have secured to the plate one of the ordinary lug caps 8 for the bouillon jar 9. For example, a cap may be removed from a jar and secured in position by means of the screws 7, and thereafter the caps of successive jars may be discarded until the cap held by plate 4 requires replacing through wear, or, for any other reason. If desired, sealing rings 10 of yielding material may be placed below cap 8 when the latter is placed in position, although these rings are not essential.

Depending from plate 4 and surrounding aperture 6 may be cast a flange 11 to deepen the aperture 6 and to provide a convenient 80 form of abutment for the dispensing cup. Flange 11 may be of the same shape as the cup, either round or angular. In the present embodiment, the flange is angular to correspond with the angular formation of the 85 cup, as shown in dotted lines, Fig. 2.

The dispensing cup is open at its top and bottom walls and is formed with horizontal top and bottom walls, the cup being indicated at 12. In Figs. 1 and 2, it will be noted that the cup is carried at one end of an arm 13 having an operating handle 13a. Intermediate its length the arm is formed with an apertured boss 14 to receive a headed stud 15 which passes through an aperture in plate 4 and which is threaded to receive a nut 16. A spring 17 surrounds boss 14 one end of the spring engaging the arm and the opposite end engaging an abutment 17 depending from cap 4, the spring being normally under 100

tension to hold the cup 12 in register with discharge opening 6. As seen more particularly in full lines, Figs. 3 and 5, and dotted lines, Fig. 2, a closure plate 12 α is carried adjacent the cup and having its top wall in line with the top wall of the cup so that when operating handle 13 α is moved to the left from its position shown in Fig. 2, in order to bring the cup to discharge position, closure plate 12 will close opening 6 as shown in Fig. 5.

Underlying cup 12 is a spring pressed plate 19. Toward one end the plate is formed with opposed ears 19 α , shown more particularly in full lines Fig. 4 and dotted lines, Fig. 2. These ears embrace a small block 20 depending from plate 4 and a pin 21 serves to pivotally connect the ears to said block. Rearwardly of the ears short plate spring 22 secured to the block by a screw 23 engages the rear edge of the plate and tends to move the same upwardly. The spring pressure imposed upon plate 19 not only serves to seal the bottom of cup 12 against leakage but also tends to carry the top wall of the cup into leakproof engagement with lower walls of flange 11, so that the device may be employed to dispense liquid from container 9 without leakage.

By references to Figs. 3 and 5, it will be noted that the cup is moved from closed position, Fig. 3, to discharge position, Fig. 5, without release of the cup from pressure by plate 19.

In order to insure quick discharge of the material from cup 12, the inner walls of the latter, or, one or more of them, may be bevelled, or outwardly flared, as shown in Figs. 3 and 5. Plate 19 acts like a knife-blade to cut or scape off any material, particularly viscous material, from the base of the cup after the latter has performed its dispensing operation and the surplus material may be received in a shallow dish 24 carried by base member 1 and preferably countersunk.

Having described my invention, what I claim and desire to secure by Letters Patent, is as follows:—

1. A dispensing apparatus particularly adapted for dispensing measured quantities of liquid, comprising a frame having a base member and standards rising from the base member, a plate for removably supporting in reversed position a container for the material to be dispensed, a dispensing cup open at top and bottom, a closure plate carried by and laterally of the cup and having its top surface in line with the upper wall of the cup, an operating handle secured to the cup, means pivotally connecting the operating handle to said plate, spring means for holding the cup normally in register with an aperture formed in the plate and for communication with said container, and a spring closure normally below the cup, said closure being held against

edgewise movement but being free for movement toward the cup.

2. A device constructed in accordance with claim 1 in which the spring closure comprises a plate which is pivotally mounted and is engaged by a spring tending to move the plate toward the base of the cup. 70

3. A device constructed in accordance with claim 1 in which the dispensing cup is formed with outwardly flared inner walls and is carried by an arm pivotally connected to the container supporting plate, said arm projecting outwardly as an operating handle. 75

4. A dispensing apparatus particularly adapted for dispensing measured quantities of liquid, comprising supporting members formed as opposed standards each standard having upwardly projecting arms, a plate formed with sets of spaced recesses to receive said arms so that the plate is removably held by the latter, an upwardly extending flange formed on the plate, means within the flange for securing a receptacle in reversed position, a downwardly extending flange formed on the plate and bounding an aperture in the latter for the passage of material from the receptacle, a cup open at the top and bottom and in contact with said depending flange, a plate below the cup normally closing the latter, an arm carried by the cup pivotally mounted on the frame and an operating handle projecting from the arm intermediate two of said standard arms. 90

In testimony whereof, I have signed my name to this specification. 100
